UNITED STATES PATENT OFFICE.

EMIL GATHMANN, OF BETHLEHEM, PENNSYLVANIA.

PROJECTILE.

No. 922,573.

Specification of Letters Patent.

Patented May 25, 1909.

Application filed March 11, 1908. Serial No. 420,386.

To all whom it may concern:

Be it known that I, EMIL GATHMANN, a citizen of the United States, residing at Bethlehem, Northampton county, State of Pennsylvania, have invented certain new and useful Improvements in Projectiles, of which the following is a specification.

The objects of this invention are to produce an armor piercing projectile containing 10 for a given size or weight and mass of head a minimum of initial strains, bordering on rupture.

Other objects are to provide a construction which allows of uniform and efficient 15 hardening and tempering of the large, as well as the small and medium sizes of armor piercing projectiles.

Further objects are to improve the details of construction of such projectiles.

20 My invention relates to that type of projectile termed armor piercing shot and shell by those familiar with the art. The head or forward portion of these projectiles are usually made very massive, and the body or 25 rear portion contains a cavity or explosive charge chamber. It is extremely desirable that the head or forward portion of the projectile be so hardened and tempered as to enable the projectile when impacting with a 30 suitable velocity to penetrate the extremely hard and tough armor plates produced by the Krupp and other systems. At the present date, specifications relating to armor 35 piercing projectiles prescribe a test in which the projectile must perforate a hard faced armor plate equal to the Krupp standard of a thickness of at least one caliber or diameter of the projectile, with the requirements that there be no breaking or cracking of any portion 40 of the latter so as to expose the charge cavity.

Although the armor piercing projectiles are at the present time being made of high grade alloy steels and are hardened and tempered with skill and care, a great many projectiles fail to pass the prescribed ballistic test. The most frequently occurring manner of failures that I have personally witnessed during the past seven years were due to the 45 shattering of the head of shell and consequent exposure or opening of the forward end of the charge cavity. This danger of shattering or rupturing of the head of the projectile upon impact with modern armor

plate becomes relatively greater, the larger 55 the size or diameter of the projectile and the more massive the forward end or head.

From the many ballistic tests of projectiles that I have witnessed and from the number of experiments made, I have determined that the shattering and rupturing of the usual construction of armor piercing projectile head, is due mainly to the excessive 60 initial strains in the mass of the metal composing the head, which strains are caused by 65 the rapid necessary cooling of the hardening processes, and the consequent shrinkage of the large mass of the outer portion of the metal upon the practically unyielding inner axial solid core or central mass of metal, 70 which being thus subjected to a compression beyond its normal shrinkage dimensions, exerts an initial outward pressure bordering on 75 rupture. I have seen a great number of armor piercing projectiles, the points and heads 80 of which have ruptured spontaneously within a short period of elapsed time after hardening treatment.

In my improved projectile, I so construct the head portion that the internal rupturing 80 strains due to hardening treatment as previously described, will be much reduced or practically eliminated. In order to obtain a good bursting effect of the projectile due to the explosion of the cavity charge of explosive 85 material, it is essential that the cavity be strongly inclosed and that no opening exists through which the gases would readily issue without properly fragmenting the shell. 90

Several forms of the invention are illustrated in the accompanying drawings, in which—

Figure 1 is a longitudinal central section of a projectile embodying the invention. Fig. 2 is a longitudinal central section of a portion 95 of a shell embodying the invention. Fig. 3 is a longitudinal section showing modified form of barrier seat.

Similar letters represent like parts throughout the drawings.

100 The practically cylindrical body A of the projectile contains a charge chamber B provided at its rear end with a threaded portion C adapted to engage with a suitable base plug D. The relatively massive head E is provided with a centrally located longitudinal bore F, said bore extending from the forward end G of the charge chamber B into the

massive head portion E, a barrier block H being provided to separate the charge chamber B from the bore F.

The barrier H is suitably secured at or 5 near the forward end of the charge chamber B; where a seat b is located, and may be built up as shown by bushings M and plug N in Fig. 1, and the said bushing M may be adapted to carry a shell fuse O if so desired, 10 as shown in Fig. 3.

A cap L of any desired form is preferably placed over the point of the projectile the cap being locked to the head of the projectile in any of the usual manners. Several types 15 of caps and methods of fastening being shown in the various figures. When the head and the point of the projectile are not formed by the same radius, but consist of two or more radii, I prefer to employ a cap 20 having its exposed or outer body portion formed of a contour approximately similar to the contour of the radius or curve forming the head of the projectile, as shown in Fig. 3 of the drawings. The splitting resistance of 25 the soft cap I have found may be advantageously increased by reinforcing its body by means of coils of wire or by stiffening collars as shown in the various figures of the drawing.

30 In hardening the head E of my construction of projectile, the mass of metal will contract inwardly in the usual manner due to rapid cooling of the same; the bore F will however allow of an inward movement or flow 35 of the metal as the natural decrease in the volume of the head takes place, thus initial strains such as obtained in a solid headed projectile will not occur, as the bore F provides for an inward flow on displacement of 40 metal, while heated and plastic, which in the solid headed projectile is impossible as the pressure on the interior solid portion caused by contraction of the outer portion results in a reactionary pressure tending to disrupt the 45 said outer portion.

It is evident, the larger the projectile the more pronounced this action, as the cooling is necessarily slower with increased diameters, the surface increasing in direct ratio to the 50 diameter, while the volume of metal increases as the square of the diameter. I would therefore vary the diameter of the shrinkage bore F and also its depth to suit the caliber of the projectile or the mass of 55 metal in the head of same, thus allowing for increased changes of volume.

If in the hardening treatment, cooling from the exterior only is desired, which method I prefer, the bore F is plugged with 60 a suitable material such as fire clay, asbestos or the like so that the cooling medium will not act on the same directly.

It will be evident that my invention may be embodied in other forms than those illustrated.

Therefore, without limiting myself to the precise construction illustrated and described, I claim:

1. An armor piercing projectile comprising a body bearing a tapering head and non-apertured point both formed integral therewith, a charge chamber within the body an axial bore within the tapered head portion and a seat for a plug located between the said bore and the charge chamber. 75

2. An armor piercing projectile comprising a body bearing a tapering head and non-apertured point both formed integral therewith a charge chamber within the body a reduced bore within the tapered head portion 80 and a plug secured between the said charge chamber and the bore.

3. An armor piercing projectile comprising a body bearing a tapering head and non-apertured point both formed integral therewith a charge chamber within the body a reduced bore within the tapered portion of the head and an inserted barrier separating the bore from said chamber. 85

4. An armor piercing projectile comprising a body bearing a conical head and non-apertured point both formed integral therewith a charge cavity within the body a reduced bore within the conical portion of the head and a threaded seat for a plug located between the bore and the said charge cavity. 90

5. A projectile having formed in one piece its body tapered head and point, a conical shaped cavity within the body a smaller cavity within the tapered head and a seat adapted 100 to engage a barrier plug located between the said cavities.

6. An armor piercing projectile having formed in one piece its body, tapering head and point, a charge cavity in the body a cavity of smaller diameter within the tapering head and a barrier interposed between said cavities in combination with a soft metal cap mounted on the point of said projectile. 105

7. A projectile having formed in one piece 110 its body, tapering head and point, a charge cavity in the body a smaller cavity within the tapering head and a seat adapted to engage a barrier located between the said cavities in combination with a soft metal cap mounted on the point of said projectile.

8. A projectile having formed in one piece 115 its body tapered head and point, the outer contour of the said head and point being formed by compound curved lines, a charge cavity within the body and a smaller cavity within the tapered head and a seat adapted to engage a barrier plug located between said cavities.

9. A projectile having formed in one piece 120 its body tapered head and point, the outer contour of the said head and point being formed by compound curved lines, a charge chamber within the body and a smaller chamber within the tapered head, a seat 125

adapted to engage a barrier plug located between said chambers in combination with a metal cap mounted upon the point of said projectile.

5. 10. A projectile having formed in one piece its body tapered head and point, the outer contour of said head and point being formed by compound curved lines, a charge chamber

within the body and a smaller chamber located in the tapered head and a barrier plug located between said chambers for the purpose set forth.
